18-178

Design No. 18,178, dated March 13, 1888.

D18178

FIG. 1.

FIG. 2.

UNITED STATES PATENT OFFICE.

FRANCIS A. COFFIN, OF INDIANAPOLIS, INDIANA.

DESIGN FOR A CABINET-DESK.

SPECIFICATION forming part of Design No. 18,178, dated March 13, 1888.

Application filed December 15, 1887. Serial No. 258,036. Term of patent 7 years.

To all whom it may concern:

Be it known that I, FRANCIS A. COFFIN, of Indianapolis, county of Marion and State of Indiana, have invented a certain new and original Design for Cabinet-Desks; and I do hereby declare that the following is a full, clear, and exact description thereof, reference being had to the accompanying engravings, which illustrates the same.

10 In the engravings, Figure 1 represents a perspective view of my newly-designed desk, all the openings being closed up. Fig. 2 is a similar view of the same, the desk-curtain being rolled back, showing the interior arrangement.

15 The desk itself belongs to that class known as cabinet-desks; and it consists of a table supported upon pedestals, in each of which is a series of drawers of different widths, and between 20 these two divisions of the desk is an open central space. Upon the top is fixed a cabinet portion inclosing a series of partitions and a couple of small drawers, with an open space between these and below them. The top is 25 closed by a flexible curtain, in the usual manner. The edges of the sides of the top and of the table portion are molded, as shown. The pedestals of the desk are separated by flat pilasters having molded bases and capitals.

30 The fronts of the drawers project beyond the face of the frame-work and have beveled edges. Plain straight handles, with beveled edges and rounded ends, are secured thereto, as shown. The small drawers in the cabinet also have 35 handles, and above and below them their fronts are finished with plain straight lines, as

is also the central piece below the table between the pedestals of the desk. The sides of the desk are paneled, the side of the top portion being of a single panel and the body portion of double panels. The escutcheon for the key-hole is fixed upon a rectangular-shaped piece, as shown.

40 The leading features of my design consist in the molded edges of the table and the top portions, the two pedestals, each containing a series of drawers of different widths, the front corners of the pedestals ornamented with flat molded pilasters with molded bases and capitals, the drawers having beveled edges and 45 beveled handles with rounded ends, as shown.

I claim—

50 The design for writing-desks herein shown and described, consisting of a cabinet-top of medium height, its ends having double-beaded curves resting upon pedestals having a central 55 open space between, each pedestal containing a series of drawers of different widths, whose fronts project beyond the face of the desk and have beveled edges, the front corners of the 60 pedestals ornamented with flat molded pilasters with bases and capitals, the drawer-handles having rounded ends and beveled edges, and the interior of the cabinet-top arranged for drawers and pigeon-holes, substantially as shown and 65 described.

In witness whereof I have hereunto set my hand this 2d day of November, 1887.

FRANCIS A. COFFIN.

Witnesses:

C. P. JACOBS,
E. B. GRIFFITH.
